UNITED STATES PATENT OFFICE

143,555

DESIGN FOR A BOWLING GAME DEVICE OR SIMILAR ARTICLE

Lois Sharpe, Glendale, Calif.

Application January 30, 1945, Serial No. 117,678

Term of patent 7 years

(Cl. D34—5)

To all whom it may concern:

Be it known that I, Lois Sharpe, a citizen of the United States of America and a resident of the city of Glendale, in the county of Los Angeles and State of California, have invented a new, original, and ornamental Design for Bowling Game Device or Similar Article, of which the following is a specification, reference being had to the accompanying drawing, forming part thereof.

In the drawing:

The figure is a front perspective view of a bowling game device or similar article showing my new design.

I claim:

The ornamental design for a bowling game device or similar article, substantially as shown.

LOIS SHARPE.
